ATTORNEY.

UNITED STATES PATENT OFFICE.

LOUIS KLEIN, OF NEW YORK, N. Y.

SPRING ARCH SUPPORT.

Application filed October 10, 1924. Serial No. 742,734.

To all whom it may concern:

Be it known that I, Louis KLEIN, a citizen of the United States, residing at New York city, in the county of New York and State 5 of New York, have invented certain new and useful Improvements in Spring Arch Supports, of which the following is a specification.

This invention relates to an improvement 10 in what I term a spring arch support and has for its object to provide an arch support, particularly adapted to be built within the shoe proper so that it will more properly conform to the shape of the foot and relieve 15 pressure from the metatarsal bones.

One of the objects of my invention is to provide an arch support for shoes which will afford a certain degree of resiliency to the foot during the act of walking, including 20 provision for correcting the unnatural position of the metatarsal bones and relieving pressure therefrom, particularly when wearing high heel shoes.

A further object of my invention is to 25 provide a spring arch support preferably constructed of light metal, such as light steel, and one which is designed to be built within the shoe proper, the front portion of the support being shaped to conform to 30 the curvature of the metatarsal bones in their natural position.

Having reference to the above objects and others which will become apparent as the 35 description of my invention proceeds, I have shown a preferred embodiment of my improved construction wherein—

Figure 1 shows the application of the invention to a conventional type of high heel shoe.

Figure 2 is a plan of the spring arch support.

Figure 3 is a side view of the support removed from the shoe.

Figure 4 is an enlarged view partly in 45 section showing the position of the spring.

Referring now to the drawings wherein like reference characters designate corresponding parts throughout the several views, 5 designates a conventional type of shoe, such as a high heel ladies' or misses' shoe in which the spring arch support is positioned, it being understood that the invention is applicable to any type of shoe wherever desired.

My invention proper consists of a base plate 6 preferably constructed of thin, resil-

ient metal, the heel portion 7 and the front portion 8 being shaped with the body of the shank of the shoe to conform to the contour of the shoe. The curvilinear edge 9 of the front portion of the support is notched at spaced intervals so that the thin metal of the support at this point will be free to expand when the weight of the body is thrown forward on the ball of the foot. An elevation 10 extending transversely of the front of the support is pressed upwardly forming a somewhat elliptical support or rest for the metatarsal bones of the foot at this point. It is a well known fact that where the foot 70 and particularly the metatarsal bones are broken down severe pain is caused by the pressure incident to the weight of the body. In providing the flat, raised support at this point in the base plate, the metatarsal bones 75 tend to lie properly, thus correcting the fit of the particular shoe. A notch 11 in the heel portion 7 permits the use of a brad 12 whereby the base plate may be positioned in the shoe.

An arch plate 13 riveted to the base plate as at 14 overlies the latter, being spaced therefrom at its center by a small coil spring 15. One end 16 of the spring is retained in a notch in the base plate and the opposite end bears against the arch plate 13 so that in the act of walking there is a certain degree of resiliency to the foot at each step thus cushioning the foot and relieving pressure to the metatarsal bones. After the 90 spring arch support is positioned in the shoe, it is covered by the usual sock lining (not shown) thus concealing the same. The arch when thus constructed of thin steel or light metal does not materially add to 95 the weight of the shoe, affords comfort and relief to the metatarsal bones and otherwise corrects the fit and shape of the shoe to the foot of the individual.

While I have illustrated and described 100 my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the subject matter being claimed.

Having thus described my invention what 110 I claim as new and desire to secure by United States Letters Patent is:—

The combination in a shoe, of an arch support of the character described comprising a base plate extending from the heel to the ball portion of the sole and shaped to conform to the shank of the said shoe, the front or anterior section of the plate having an elliptical, transverse elevation and the

edge of said plate being notched whereby it may expand, a narrow arch plate overlying the base plate and a spring interposed between the said base and arch plates.

In testimony whereof I have affixed my signature October 1924.

LOUIS KLEIN.
